It is certified that error appears in the above-identified patent and that said Letters Patent is hereby corrected as shown below:

In the Drawings, Figures 1-4 and 9-12 should be deleted. Figures 5-8 were elected in response to the Restriction Requirement of June 17, 2011. Accordingly, Figure 5 should be renamed Figure 1; Figure 6 should be renamed Figure 2; Figure 7 should be renamed Figure 3; and Figure 8 should be renamed Figure 4.

In the Description, lines 1-8 and lines 17-25, which correspond to written descriptions of the non-elected Figures, should be deleted.

In the Description, lines 9-10 should appear as follows: "FIG. 1 is a perspective view of an LED lamp according to an embodiment of the present invention."

In the Description, lines 11-13 should appear as follows: "FIG. 2 is a front elevation view of the LED lamp shown in FIG. 1, with the rear and side views substantially identical in ornamental appearance."

In the Description, line 14 should appear as follows: "FIG. 3 is a top plan view of the LED lamp shown in FIG 1."

In the Description, lines 15-16 should appear as follows: "FIG. 4 is a bottom plan view of the LED lamp shown in FIG 1 ."

In the Description, lines 26-27 should appear as follows: "The broken lines shown in FIGS. 1-4 depict environmental subject matter only and form no part of the claimed design."
